UNITED STATES PATENT OFFICE

134,248

DESIGN FOR A PORTABLE BARBECUE BROILER

James H. Reichart, Muncie, Ind.

Application March 25, 1942, Serial No. 106,327

Term of patent 14 years

To all whom it may concern:

Be it known that I, James H. Reichart, a citizen of the United States and a resident of Muncie, county of Delaware, and State of Indiana, have invented a new, original, and ornamental Design for a Portable Barbecue Broiler, of which the following is a specification, reference being had to the accompanying drawing, forming part thereof.

In the drawing, Fig. 1 is a front perspective view of a portable barbecue broiler, embodying my new design, and Fig. 2 is a rear perspective view thereof.

The device illustrated is substantially identical at opposite ends. The dominant features of the design reside in the portions shown in full lines.

I claim:

The ornamental design for a portable barbecue broiler, substantially as shown and described.

JAMES H. REICHART.
